(57) **CLAIM**

I claim the ornamental design for an adult toy stand apparatus, as shown and described.

DESCRIPTION

FIG. 1 is a front perspective view of the adult toy stand apparatus;

FIG. 2 is a second front perspective view of the adult toy stand apparatus shown in an alternate condition of use thereof;

FIG. 3 is a rear perspective view of the adult toy stand apparatus;

FIG. 4 is a front elevational view of the adult toy stand apparatus;

FIG. 5 is a rear elevational view of the adult toy stand apparatus;

FIG. 6 is a top plan view of the adult toy stand apparatus;

FIG. 7 is a bottom plan view of the adult toy stand apparatus;

FIG. 8 is a left side view of the adult toy stand apparatus;

FIG. 9 is a right side view of the adult toy stand apparatus; and,

FIG. 10 is a second right side view of the adult toy stand apparatus.

The shading lines shown in the drawings represent the approximate three-dimensional contour of the design, and are not intended to indicate surface decoration.

The broken lines indicate portions of the adult toy stand apparatus that form no part of the claimed design.
